UNITED STATES PATENT OFFICE.

RAY W. FRANKLIN, OF MONTICELLO, IOWA, ASSIGNOR TO FRANKLIN BARN EQUIPMENT COMPANY, OF MONTICELLO, IOWA, A CORPORATION OF MAINE.

STANCHION.

1,322,686.

Specification of Letters Patent. Patented Nov. 25, 1919.

Application filed February 24, 1919. Serial No. 278,905.

To all whom it may concern:

Be it known that I, RAY W. FRANKLIN, a citizen of the United States of America, and a resident of Monticello, Jones county, 5 Iowa, have invented certain new and useful Improvements in Stanchions, of which the following is a specification.

My invention relates to improvements in stanchions, and particularly to stanchions having paired standards, of which one is movably connected to the other, and the object of my improvement is to furnish a movably linked connection for such standards, and manually operable fastening means for 15 separably securing them together in a closed position relative to each other.

This object I have accomplished by the means which are hereinafter described and claimed, and which are illustrated in the 20 accompanying drawings, in which Figure 1 is an elevation of my improved stanchion and its supporting means, with parts broken away; Fig. 2 is a detail elevation of the stanchion, partially in section, with the movable standards thereof, swung outwardly; Fig. 3 is a top plan view of the stanchion shown in said Fig. 2, and Fig. 4 is an enlarged detail sectional view of the pivotal connection of the movable standard.

Similar numerals of reference denote corresponding parts throughout the several views.

My improved stanchion is composed of a fixed standard 1 and a swinging standard 2 35 with cross connections 3 and 23 at the top and bottom respectively. Said cross connections have respectively grooved sockets 16 and 21 within which are fixedly mounted the ends of the standard 1, both of the standards 1 and 2 being made of T-bars, but may be constructed in tubular form or in any desired suitable cross section. The lower cross connection 23 has opposite its socket 21 a socket 22, which is shown in section in Fig. 4. This socket has that part of its inner wall 24 which abuts upon the adjacent standard 2 sloped inwardly, and the standard 2 is pivotally mounted in said socket on a pintle 25. On opposite sides of the web of 50 said standard are fixed spacing-plates 26 which fill up the interspaces between opposite sides of said web and opposite walls of said socket to contact therewith. The inclined wall part 24 of said socket affords 55 room for the standard 2 to swing outwardly

restrictedly, but the upper angle thereof serves as a stop to limit swinging movement of the standard in the opposite direction.

The upper cross-connection 3 has a vertically disposed slot 4 through which is passed 60 the pintle 5 connecting the depending members of a swivel 6. The numeral 31 denotes a pair of spaced vertical posts set fixedly in a solid base made of concrete or other material. Said posts are connected at their 65 tops by a cross-beam 32 mounted in pairs of clamping-members 33. A hook 8 is fixed dependingly in the middle of the cross-beam 32, and the swivel 6 is connected to said hook by several chain links 7. By said means, the 70 stanchion is swingingly supported and freely movable in any direction, but will always return automatically to the normal plane of its position between and relative to said posts, because of the directive action of said 75 chain links and swivel connection in the slot 4.

The lower cross-connection 23 has a horizontally disposed slot 27 receiving a ring 28. An eye-bolt 29 whose shank is bent angularly and fixed within the base 30, is connected to the ring 28 by several chain links, 80 which permit restrictive movements of the stanchion in any direction.

The upper end of the swinging stanchion 85 2 is movably linked to the upper cross connection 3 by the following means: Said upper cross connection has a longitudinal tubular hollow 18 open through a socket 14, the latter adapted to seat the upper end of the 90 standard 2. A body is fixed upon the upper end of the standard 2 provided with an outwardly directed integral fork 19 adapted to span the adjacent post 31 to limit movement of the stanchion when said standard 2 is 95 swung outwardly. Said body also has an upwardly directed detent 17. The numeral 20 denotes an elongated loop, the ends of which are swingingly connected to said body on pivots 35. The loop 20 is receivable and 100 movable slidably within the hollow 18 of said cross connection 3, and is prevented from escaping from said hollow by means of a fixed stud or pin 34 fixed across said hollow near its outer end within said loop. The cross connection 3 has spaced parallel 105 longitudinal ribs 36 on its top between which is mounted a lever 10 medially pivoted on a pintle 9, and having one end enlarged at 13 and provided with a downwardly directed 110

sloping socket 12 to receive and fit the sloping detent 17 on said standard 2. The other end of said lever passes through said swivel 6 above its pintle 5 and is formed into a finger piece 11. The pintle 5 engages the superposed part of the lever 10 to keep the engaging-means 12 thereon in engagement with the detent 17.

When the movable standard 2 is in the position shown in said Fig. 2, it may be swung inwardly, thus sliding the loop 20 into the hollow 18 of the cross-section 3 until the upper end of the standard is received between the forks of the socket 14. Said standard 2 is so located relatively to the socket 14 that when swung inwardly, it will not completely fit said socket without slightly bending, and since the T-bar part of said standard is somewhat elastic, it will yield sufficiently for the purpose, when, as shown in Fig. 4, it is engaged with the angle of the sloping inner wall 24 of the lower socket 22, the pintle 25 serving as a fulcrum. It is only in this position that the detent 17 will be immediately below the socket 12 of the trip-lever 10, and since this end of said lever is heavier than its other end, it will drop and receive said detent within its socket, which securely fastens the standard 2 to the trip-lever because the elastic reaction of the standard causes the sloping face of the detent to interlock with the abutting sloping inner wall of the socket 12. The standard 2 may be spread apart to its first position by simply depressing the finger-piece 11 of the trip-lever, which draws back the standard elastically enough to cause the detent 17 to escape from the socket 12 as the head 13 of the lever is swung upwardly. This drawing inwardly of the standard 2 has again placed it under tension, and on the release of the detent 17, the reaction of said tension is sufficient to thrust outwardly the standard slightly beyond the center of gravity so that, under the influence of gravity, it will swing outwardly, withdrawing the loop 20 from the socket 18, and engaging the forks 19 with the adjacent post 31.

It should be noted that the looped bar 20 is of relatively great strength transversely, and guides the upper end of the standard 2 directly into the socket 14 without fail, while the support afforded by this bar to the upper end of the standard takes away strain from the hinged connection at its lower end, preventing breakage in the hinge, or bending of the standard if pushed violently by a shoulder of the cow.

When the standard 2 is swung to its closed position, the clash of its upper part with the socket 14 reacts on the pivoted lever or catch 13 to shake the latter into engagement with the projection 17 and prevent sticking of the lever on its pintle.

The means shown are easily operated manually, act automatically when the initial impulse has been given, while the locking action is such that the parts cannot be separated by ordinary shocks and jars, and in fact, only by a positive depression of the finger-piece 11 of said trip lever.

Having thus described my invention, what I claim as new, and desire to secure by Letters Patent, is:

In combination, a pair of pivotally connected stanchion standards, a cross-connecting body fixed to the top of one standard and provided with a raised part having a vertically-elongated orifice, engaging-means on the upper end of the other standard, a trip-lever having engaging-means to mate with the other engaging-means and pivoted on said cross-connection, said lever extending above said elongated orifice, and supporting-means including a pintle passed through said elongated orifice to support the cross-connection movably while engaging the superposed part of said lever to keep the engaging-means thereon in engagement with the engaging-means on said other standard.

Signed at Monticello, Iowa, this 7th day of Feb., 1919.

RAY W. FRANKLIN.
